UNITED STATES PATENT OFFICE.

EDMUND C. FEY, OF SAN FRANCISCO, CALIFORNIA.

GALLERY RIFLE.

Application filed September 13, 1926. Serial No. 134,956.

The present invention relates to an electrically controlled marksmanship practice apparatus in which the projectiles are eliminated and the results of accurate aim and timely firing are attained through the coordination of electrical mechanism.

The object of the invention consists in providing an electrically controlled apparatus which will test the skill of the marksman in aiming the rifle upon the moving target in order to produce a high score, which consists in making a consecutive number of direct hits, out of any given number of shots.

With the above mentioned and other objects in view, the invention consists in the novel construction and combination of parts hereinafter described, illustrated in the accompanying sheet of drawings, and set forth in the claims hereto appended, it being understood that various changes in the form, proportion, size, and minor details of construction within the scope of the claims may be resorted to without departing from the spirit or sacrificing any of the advantages of the invention.

In the accompanying drawing, wherein

Figure 1 is a view in side elevation, partly in section, of the invention showing the contact pin above the contact plate, the armature and electro-magnet being in their normal position.

Figure 2 is a front elevation of the moving targets showing the electrical connections between the electro-magnets and their respective contact plates.

Figure 3 is an end elevation showing the armature drawn backwards by the electro-magnet thereby releasing the target.

Figure 4 is a view taken on line 4-4 of Figure 1 showing the means provided on the armature and target for retaining the target in a vertical position.

Figure 5 is a view of a modified form of circuit arrangement. Figure 6 is an end view of a target with the electro magnet and armature movable therewith.

In the drawing wherein like characters of reference designate corresponding parts, 1 represents an aiming element in the form of a projectless rifle having a trigger 2 and a hammer 3, said rifle being mounted upon a base 4 through a universal joint 5 enabling the rifle to be moved in any desired position. A tubular rod 6 depends from the underside of the universal joint 5, the portion

6' of said rod being universally fulcrumed at 7 within the base 4, and the ends of said rod 6 and portion 6' being connected by a ball and socket joint 7', thereby maintaining 60 said portion 6' in a substantially perpendicular position at all times. A contact pin 8 is freely held within the rod 6 by one end of a flexible wire, not shown, which extends throughout the rod and is fastened to the hammer 2; said pin being free to reciprocate when the hammer 2 is moved back and forth. Directly beneath the contact pin 8 are a plurality of individual contact plates 9 mounted in series and separated from one another 65 by insulation material 10. The edges of the contact plates 9 are inclined as at 11 to deflect the pin 8, in its downward movement upon the contact plate and not allow the same to rest upon the insulated material 70 separating said plates.

Positioned in front of the rifle 1 are the traveling targets 12 each pivotally connected with the respective links of an endless chain 13, the latter being propelled by 80 any suitable means, such as a motor 14, and prevented from sagging by a track 15 on which the same slides. A relatively narrow finger 16 extends laterally from the face of each target. A series of armatures 17 are 85 pivotally mounted in front of the moving targets, and each is provided with a hook 18, said hooks being of a width corresponding to that of the base of the targets 12, and are adapted to overlie the fingers 16 as the moving targets pass in rear thereof in their line of travel, thus sustaining the targets in a vertical position. An electro magnet 19 mounted on insulation 20 is positioned in front of each armature 17.

Electric current supplied by a battery 21 is carried by the wire 22 to the armatures 17. Current is also supplied to the contact pin 8 by said battery through the wire 23 which is connected to the tube 6.

The respective contact plates 9 are connected to their respective electro-magnets 19 by wires 24. When the firing pin is released it closes the circuit energizing the electro-magnet 19 connected with the plate 9 lying beneath the pin 8, which draws the armature 17 associated with the magnet backward away from the finger 16 of the moving target in rear of the armature at which the gun is pointed, thus if the marksman accurately aims the gun on the center of the moving target, and pulls the trigger 2, the

target aimed at will drop to the position in Figure 3. A weight 25 carried on the back of the target causes the same, when released, to tip backward into the horizontal position, as shown in Figure 3.

Thus it will be seen that when the rifle 1 is moved in aiming upon one of the moving targets, the rod 6, carrying the contact pin will move horizontally over the contact 10 plates 9 until the same overlies the contact plate associated with its respective electro-magnet and armature supporting the selected moving target. The operation of the trigger causes the contact pin to drop upon 15 the contact plate completing the circuit causing said electro-magnet to draw the armature backwards releasing the target.

In Figures 5 and 6 is illustrated a form of the invention wherein two separate rail 20 sections 26 and 27 insulated from each other are employed, the rail section 26 consisting of corresponding sections or portions 28 insulated from each other, forming independent contacts, and the section 27 being continuous, forming a single contact common to 25 all of said independent contacts. Longitudinally of the rails moves a chain, divided longitudinally into two sections 29 and 29', insulated from each other, and each adapted 30 to slide along the respective rails 26 and 27. The longitudinal section 29 cooperating with rail section 26 is transversely insulated into sections at 30. Each section 30 carries an electro-magnet 31, and corresponding 35 sections 29' carry pivotally mounted targets 12 and cooperating armatures 31', thus opposing segments of corresponding chains carry a target and the holding and releasing means therefor.

40 In the construction illustrated in Figure 5, the circuit is the same as in the preferred form, excepting that the circuit is completed through the corresponding portions 28 of rails 26 and 27 and the corresponding links 45 of the chain sections 29 and 29', at such time as contact is made with the member 9.

I claim:—

1. A device for the described purpose comprising an aiming element; a plurality 50 of electric switches; means operatable in accordance with the aim of said element for severally controlling said switches; a target normally out of the aiming range of the aiming element, means for moving the same across the aiming range of the aiming element; a succession of electrically operated target tripping means to indicate accurate aim; and electric circuits between said switches and target tripping means.

60 2. A device for the described purpose comprising an aiming element; a plurality of electric switches; means operatable in accordance with the aim of said element for severally controlling said switches; a traveling target; a succession of armatures past

which said target moves; a succession of electro-magnets positioned in front of said armatures to operate the same for tripping said target to indicate accurate aim, and electric circuits between said switches and 70 electro-magnets.

3. A device for the described purpose comprising an aiming element; a plurality of electric switches; means operatable in accordance with the aim of said element for severally controlling said switches; a traveling target; a finger carried by said target; a succession of armatures past which said target moves, said armatures overlying said finger as said target passes thereby; a succession of electro-magnets positioned in front of said armatures to operate the same for tripping said target to indicate accurate aim, and electric circuits between said switches and electro-magnets. 85

4. A device of the class described, comprising an aiming element, a traveling target pivotally mounted on a horizontal axis disposed parallel with the direction of travel of the target and normally out of aiming 90 range of the aiming element and movable across the aiming range of said aiming element, an electric circuit, and a switch in said circuit operatable for completing the electric circuit to trip the target on an accurate aiming of said aiming element on the target during its movement across the aiming range of the aiming element. 95

5. A device for the described purpose comprising an aiming element, a plurality 100 of electric switches, means operatable in accordance with the aim of said element for severally controlling said switches, a traveling target, a finger carried by said target, an armature with which said target cooperates, 105 said armature overlying said finger, an electromagnet positioned in front of said armature to operate the same to trip said target to indicate accurate aim, and an electromagnet between said switches. 110

6. A device for the described purpose comprising an aiming element, a plurality of electric switches, means operatable in accordance with the aim of said element for severally controlling said switches, a plurality 115 of traveling targets, armatures cooperating with said targets, electromagnets cooperating with said armatures to operate the same for tripping one of said targets to indicate accurate aim, and electric circuits 120 between said switches and electromagnets.

7. A device for the described purpose comprising an aiming element, a plurality of electric switches, means operatable in accordance with the aim of said element for severally controlling said switches, a plurality 125 of traveling targets, each mounted for pivotal movement on a horizontal axis, disposed parallel with their line of travel, armatures cooperating with said targets, 130

electromagnets cooperating with said armatures to operate the same for tripping one of said targets to permit the same to swing on its horizontal axis to indicate accurate aim, and electric circuits between said switches and electromagnets.

8. A device for the described purpose comprising an aiming element, an electric switch, means operable in accordance with 10 the aim of said element for controlling said switch, a traveling target mounted for pivotal movement on a horizontal axis disposed parallel with its line of travel and normally out of the aiming range of the 15 aiming element, means for moving the target across the aiming range of the aiming element, an armature cooperating with said target, an electromagnet cooperating with said armature to operate the same to trip

said target to permit the same to swing on 20 its horizontal axis to indicate accurate aim, and an electric circuit between said switch and electromagnet.

9. A device of the class described, comprising an aiming element, a travelling target movable from aiming to hit indicating position and further movable within the aiming range of said aiming element, an electric circuit, and a switch in said circuit operable for completing the electric circuit 25 to trip the target to permit its movement from aiming into hit indicating position on an accurate aiming of said aiming element on the target during its movement within the 30 aiming range of the aiming element.

In testimony whereof I have signed my name to this specification.

EDMUND C. FEY.
